UNITED STATES PATENT OFFICE.

PAUL NORTH, OF LAKWOOD, OHIO.

TARGET TRAP.

Application filed February 16, 1925. Serial No. 9,476.

To all whom it may concern:

Be it known that I, PAUL NORTH, a citizen of the United States, residing at Lakewood, in the county of Cuyahoga and State of Ohio, have invented a certain new and useful Improvement in Target Traps, of which the following is a full, clear, and exact description, reference being had to the accompanying drawings.

10 This invention relates to target traps, and has for its general object to improve the efficiency and flexibility of the same.

As target traps have been constructed heretofore, the arm which throws the target 15 is held in its throwing position by a trigger which is mechanically released by the engagement of an ordinary yoke therewith, the yoke being moved into such engagement through the operation of a pulling lever.

20 The throwing arm being latched in throwing position by the trigger and the target being in place, the operator pulls the said lever back a more or less variable distance and holds it in such position until the shoot-

25 er gives the order "pull", whereupon, by a shorter further movement of the lever, the yoke engages the trigger and trips the same, releasing the throwing arm. If the distance to which the pulling lever is preliminarily 30 moved is too short, then there will be too long an interval between the giving of the order to pull and the release of the throwing arm. Where such delay exceeds a cer-

35 tain time, what is known as an "illegal" target will be thrown, making it necessary to throw another target in place of such illegal one. Each such illegal target prolongs correspondingly the time required for the event, unnecessarily delaying the operations.

40 Furthermore, as is well known, the most aggravating feature of trap shooting is the employment of a slow or irregular "pull", which is inherent in the mechanically-operated releasing mechanism of traps now in 45 use.

I overcome the objections noted hereinbefore by the employment of electrically-operated releasing mechanism, which may be, and preferably is, embodied in an ordinary type of trap having a pulling lever, but which mechanism is so arranged as to enable the pulling lever to be first pulled or set to a definite position, after which the

throwing arm may be instantaneously released upon the call of "pull" by the shooter. 55 This capability of setting the lever to a definite position insures a uniformly proper distance to the flight of the targets. Furthermore, if desired to vary the tension of the throwing spring, thereby to vary the 60 flights of the targets at any time or to accommodate wind conditions, provision is made for adjusting the definite point to which the lever may be pulled or set before releasing the throwing arm. Still further, 65 by a small adjustment, the trap may be adapted for what is known as "sporty" shooting, enabling the operator to release the throwing arm at any point in the movement of the pulling lever, but to accomplish 70 such release immediately after the call of "pull".

I accomplish the foregoing objects and other and more limited objects which will be explained hereinafter in and through the 75 construction and arrangement of parts shown in the drawings, wherein Fig. 1 represents a side elevation of a target trap having my invention applied thereto; Fig. 2 a plan view of the platform and cooperating 80 parts; Fig. 3 a detail in vertical section of the trigger mechanism, showing the throwing arm in section; and Fig. 4 a detail in sectional elevation of the trigger and the means for operating the same, the electric 85 circuit being shown diagrammatically.

For the throwing portion of the trap, I have shown herein a construction and arrangement of parts substantially identical with that illustrated in my Patent No. 90 1,506,992 issued September 2, 1924, although my invention is capable of being used with other forms and constructions of traps.

In the form shown herein, the throwing portion of the trap comprises generally a 95 sub-base 1, carrying a tilting base which is pivoted to the sub-base at 2, the tilting base having a central standard 3 to which the frame 4 may be connected by means of a bolt 5 extending through said standard and 100 a downwardly extending projection 4^a of said frame. Where a tilting base is employed, a shaft 6 is used for operating the tilting base, the said shaft being shown as provided with a worm 7 meshing with a 105 worm gear 8 on a shaft 9, which shaft is

connected (as by means shown in my patent aforesaid) with the tilting frame, thereby to rock the same about the pivot 2. A spring 10 tends to lift the front or swinging end of the tilting frame. As pointed out hereinbefore, the base which supports the frame 4 may be of any desired construction, the one shown herein being my present preferred form. The frame 4 supports a platform or table 11 having a throwing arm 12, the said arm being operated in the usual manner through a crank arm 13, a throwing spring 14, and a resetting spring 15. The lower and rear end of the spring 15 is connected to the lower end of an arm 16 pivoted to the frame 4, as indicated at 16^a. Connected to the arm 16 is the pull rod 17, the same being connected in the usual manner to the pulling lever 18, which is pivoted at 20 its lower end in the pulling stand 19, as shown at 19^a. The pulling lever is also connected in the usual manner to the spring 20, the rear end of the said spring being adjustably connected to the rear of the pulling stand 19 by means of a bolt 21.

For the purpose of adapting my releasing mechanism to a trap such as thus outlined, I employ a trigger for holding the arm 12 in its throwing position, a solenoid for operating said trigger, and circuit-closing means associated with and operated by the pulling lever 18 for operating the trigger and releasing the said arm. The detailed construction of this releasing mechanism will now be described:—22 denotes the stem of the trigger, the said stem and the trigger latch 22^a being mounted within a recess 23 in the frame 4. The upper end of the latch is rounded or beveled, as shown at 22^b, to permit the arm 12 to ride thereover and depress the trigger until the arm passes thereby and abuts against the stop 24, whereupon the spring 25 which surrounds the stem and bears against the head 22^a will move the latch into engagement with the arm.

The stem 22 projects through the frame 4 and is provided with a slot 22^c therein through which there extends a link 26, the said link being pivoted at one end to a projection on the frame, as indicated at 26^a. The link 26 also extends through a slot 27^a in the upper end of a rod 27 forming an extension of the core of a solenoid 28. Wires 29 and 30 extend from said solenoid, the wire 29 being connected with the pulling lever 18 and the wire 30 being connected to a binding post 31^a on a lever arm 31 which is pivoted to the pulling stand 19, as indicated at 31^b. A contact spring 32 extends rearwardly from the arm 31 and is adapted to engage a contact 33 on a projection 34 of a slidable block 35, said block being mounted upon a base 36. The block 65 is secured to the base by means of a bolt

37 and a nut 37^a. In order to vary the tension of the throwing spring as occasion may require, the block 35 is provided with a slot 35^a through which the clamping bolt extends. A wire 37 connects the projection 34 with the pulling lever 18, said pulling lever having a handle 18^a at its upper end and a switch button 38 adapted, when depressed by the thumb of the operator, to close the circuit between the wires 29 and 37. A spring 39 normally holds the arm 31 away from the projection 34, preventing the engagement of the spring contact 32 with the contact 33.

With the parts constructed and arranged as described the operation will be readily understood.

The throwing arm 12 is swung behind the latch head 22^b and a target or targets 40 will be placed upon the platform, preferably beneath a retaining frame 41. The operator then moves the pulling lever rearwardly, this movement causing the lever to engage the arm 31 and to move said arm rearwardly until, at the point of rest, the contacts 32 and 33 will be in engagement. As soon as the order to "pull" is given, he presses the button 38 thereby closing the circuit through the solenoid 28, which will cause the core and its extension 27 to move downwardly, pulling the trigger 22—22^b downwardly and releasing the arm 12.

Through the construction and arrangement of parts shown and described herein, the operator must always pull the lever 18 rearwardly to a predetermined position before the arm 12 can be released, this predetermined position being determined by the engagement of the arm 31 with the projection 34, as indicated in dotted lines on Fig. 1. Should it be desired to vary the tension of the spring 15, thereby to vary the throw or flight of the targets, the adjustability of the block 35 (which carries the contact 33) will enable such adjustment to be made, but without interfering with the instantaneous release of the arm 12 as soon as the order to "pull" shall have been given.

When it is desired to impart to trap shooting the "sporting" feature referred to hereinbefore, this may be readily accomplished by disconnecting the wire 30 from the post 31^a and connecting it to the post 33, thus leaving the circuit unclosed only at the switch button 38. The operator can then release the arm 12 at any position of the pulling lever 18, thereby varying the tension of the spring 15, with corresponding variations in the flights of the targets.

By placing the switch-button 38 on the lever 18, the lever can be pulled and the trigger released by the same operator.

Having thus described my invention, what I claim is:—

1. In a target trap, the combination, with a throwing spring, a throwing arm operatively connected with said spring, a pull rod for said spring and a pulling lever connected with said rod, of a trigger for holding the arm in throwing position, electrical means for operating said trigger to release said arm, and a circuit-closing device carried by and movable with the pulling lever for operating the said means. 5
2. In a target trap, the combination, with a throwing arm, means including a pulling lever for throwing said arm, and a device for holding said arm in throwing position, of electrical means for operating said device to release said arm, and a circuit-closing device carried by and movable with the pulling lever for operating the said electrical means. 15
3. In a target trap, the combination with a throwing arm, means including a pulling lever for throwing said arm and a device for holding the arm in throwing position, of electrical means for operating the said device to release the said arm, the said means comprising a circuit, and switch mechanism for said circuit adapted to be closed by the movement of said lever to a predetermined position. 25
4. In a target trap, the combination, with a throwing spring, a throwing arm operatively connected with said spring, a pull rod for said spring and a pulling lever connected with said rod, of a trigger for holding the arm in throwing position, and electrical means for operating the said trigger, the said means comprising a circuit having a switch mechanism adapted to be closed by the pulling movement of the said lever, and switch mechanism carried by the said lever and adapted to be operated independently of the first mentioned switch mechanism. 35
5. In a target trap, the combination, with a throwing spring, a throwing arm operatively connected with said spring, a pull rod for said spring and a pulling lever connected with said rod, of a trigger for holding the arm in throwing position, and electrical means for operating the said trigger, the said means comprising a circuit having switch mechanism adapted to be closed by the movement of the said lever to a predetermined position, and switch mechanism carried by the said lever and adapted to be operated independently of the first mentioned switch mechanism. 50
6. In a target trap, the combination, with a throwing spring, a throwing arm operatively connected with said spring, a pull rod for said spring and a pulling lever connected with said rod, of a pulling stand, a trigger for holding the arm in throwing position, and electrical means for operating the said trigger to release the said arm, 65
- the said means comprising a circuit having a solenoid therein, a connection between said solenoid and said trigger, a switch on said stand adapted to be closed by the engagement thereof by a contact carried by said lever, a switch carried by and movable with said lever, and means on said lever for closing said switch. 70
7. In a target trap, the combination, with a throwing spring, a throwing arm operatively connected with said spring, a pull rod for said spring and a pulling lever connected with said rod, of a pulling stand, a trigger for holding the arm in throwing position, and electrical means for operating the said trigger to release the said arm, the said means comprising a circuit, and means operated by the closing of said circuit for releasing said trigger, said circuit-closing means comprising a contact carried by said stand, a movable contact on said stand normally spaced from the first mentioned contact and adapted to be engaged by said pulling lever, thereby to close the circuit through said contacts, a switch in said circuit carried by said lever, and a switch-closing member on said lever. 85
8. In a target trap, the combination, with a throwing spring, a throwing arm operatively connected with said spring, a pull rod for said spring and a pulling lever connected with said rod, of a trigger for holding the arm in throwing position, and electrical means for operating the said trigger, the said means comprising an electric circuit, a contact in said circuit, a second contact operative by the pulling movement of the said lever to engage the first-mentioned contact, and means for varying the position of the first contact, whereby the said circuit may be closed at correspondingly varying positions of the said lever, and with corresponding variations in the tension of said spring. 95
9. In a target trap, the combination, with a throwing spring, a throwing arm operatively connected with said spring, a pull rod for said spring and a pulling lever connected with said rod, of a pulling stand, a trigger for holding the arm in throwing position, and electrical means for operating the said trigger to release the said arm, the said means comprising a circuit, and means operated by the closing of said circuit for releasing said trigger, said circuit-closing means comprising a contact carried by said stand, a movable contact on said stand normally spaced from the first mentioned contact and adapted to be engaged by said pulling lever, thereby to close the circuit through said contacts, a switch in said circuit carried by said lever, and a switch-closing member on said lever, the first mentioned contact being adjustable whereby it will be engaged by the second 100
- 110
- 115
- 120
- 125
- 130

contact in varying positions of the pulling lever, with corresponding variations in the tension of the throwing spring.

10. In a target trap, the combination, 5 with a frame, a throwing arm, a throwing spring operatively connected to said arm and a pulling lever connected to said spring, of a trigger for locking the said arm in throwing position, and electrical means for 10 operating the said trigger, the said means

comprising a solenoid carried by said frame, said solenoid having a core operatively connected with said trigger and a circuit including the said solenoid and adapted to be closed by the said lever when the latter shall have been moved a predetermined distance in its pulling direction. 15

In testimony whereof, I hereunto affix my signature.

PAUL NORTH.
